UNITED STATES PATENT OFFICE.

CHARLES LORBER, OF LOUISVILLE, KENTUCKY.

KEY CASE.

Application filed March 7, 1927. Serial No. 173,303.

This invention relates to key cases and has special reference to a key case of the type intended for carrying keys in the pocket of the user.

5 One important object of the invention is to provide an improved means for suspending the keys in such a key case wherein a novel arrangement of a swiveling key hook will be so carried on a plate or support attached to 10 the body of the case that the hook may have free swinging movement in any direction and may be rotated on its axis in any position which it may assume.

A second important object of the invention 15 is to provide an improved arrangement of this class wherein the plate or support is so constructed that the keys may be swung to lie against either side of the body of the key case to which such support is attached.

20 A third important object of the invention is to provide a novel form of support for the key holders which may be made of flexible material, such as leather or the like and wherein swiveling key holders may be held to 25 lie at will on either side of that portion of the body of the key case to which the supporting member is attached.

With the above and other objects in view as will be hereinafter apparent, the invention 30 consists in general of certain novel details of construction and combinations of parts hereinafter fully described, illustrated in the accompanying drawings and specifically claimed.

35 In the accompanying drawings like characters of reference indicate like parts in the several views, and:

Figure 1 is a view of a key case constructed in accordance with this invention with the 40 case shown open.

Figure 2 is a detail section on the line 2—2 of Figure 1.

Figure 3 is a section similar to Figure 2 but showing a modified form of key holder 45 by means of which the key may be positioned on either side of the portion of the case proper.

Figure 4 is a detail view of a modified form of supporting member preferably constructed 50 of flexible material.

Figure 5 is a section on the line 6—6 of this modified member.

Figure 6 is a section similar to Figure 3 but showing the modified member.

55 Figure 7 is an enlarged view of one of the key hooks and its swivel ring.

In carrying out the invention there is provided the ordinary leather case having the back portion 10 and cover flaps 11 which are arranged to close on each other and then held in closed position by means of snap button parts 12 riveted to said flaps. Each of the hooks used to suspend the keys is preferably made of a strip of flat metal bent to form an eye 13 at its upper end and continued downwardly from the eye is a shank 14 which merges into the bight or bottom 15 of the hook. The material is then extended upwardly and toward the shank 14 to contact with said shank adjacent the eye 13 and the end of the hook is bent outwardly to provide a bill 16. Above each eye 13 there is provided an attaching ring 17 having a shank 18 which passes through the metal of the ring 13 opposite the bottom of the hook 15 and in alinement with the centers of said bottom and the eye 13. Within the eye 13 the shank 18 is flattened or upset to provide a head 19. By this means the hook is swivled to the ring 17. In the form of the invention shown in Figures 1 and 2 there is provided a plate 20 which is suitably secured to the portion 10 at its upper part and along the upper edge of this plate there is provided a series of fingers which are bent 85 forwardly and downwardly to form supporting eyes 21 engaging the rings 17. As shown in Figure 2 the supporting eyes 21 do not project over the top of the portion 10 but in Figure 3 these eyes are flattened and 90 elongated as at 22 so that one end of each eye lies in front of the part 10 while the other end lies to the rear thereof. Thus the ring 17 can be swung to either the full or dotted line positions shown in Figure 3 so 95 that a key suspended on the hook may lie either against the front or the rear side of said portion 10.

In the form of the supporting member shown in Figures 4 and 5 a flat strip of 100 flexible material such as leather or the like is provided with slots 23 and doubled upon itself to form supporting eyes 24 for the rings 17. This doubled strip is sewed to the portion 10 by stitch lines 25. In the form 105 shown in Figure 6 the slots are of sufficient length that the supporting eyes 26 may lie, as in Figure 3, with their ends on opposite sides of the portion 10 and thus the hook and the key carried thereby may be positioned 110 either in front or in back of said portion 10. It will be observed that with this construc-

tion the hook can not only be swung in a plane perpendicular to the axis of the eyes 21 but can also be swung sideways as the ring 17 will slip readily through its supporting eye. Moreover, the hook, and consequently the key carried thereby, may be rotated on the swivel connection to any desired position. Thus a high degree of flexibility is provided for the attachment of the 10 keys to the key case.

There has thus been provided a simple and efficient device of the kind described and for the purpose specified.

It is obvious that minor changes may be 15 made in the form and construction of the invention without departing from the material spirit thereof. It is not, therefore, desired to confine the invention to the exact form herein shown and described, but it is 20 desired to include all such as properly come within the scope claimed.

Having thus described the invention, what is claimed as new, is:

1. In a key case, a body member, a supporting member mounted against one side of the body member and having a series of eyes at

its upper edge, the eyes each projecting away from the body member in a relatively short projection and across the upper edge of the body member in a relatively long projection 30 whereby key holders engaged in said eyes may lie flat against the body member on one side and supporting member on the other, and key holders each engaged in a respective eye.

2. In a key case, a body member, a supporting plate mounted on the body of the case adjacent the upper edge thereof and having a series of spaced eyes at the upper end thereof, rings each engaging in a respective eye for free swinging and rotative movement therein, a shank projecting radially from each ring, and key hooks each having an eye at its upper end provided with an opening wherethrough the shank of a respective ring passes, the portion of the shank within the hook eye being upset to constitute a head whereby the hook eye is prevented from disengagement from the shank and has free swiveling movement thereon.

In testimony whereof I affix my signature.

CHARLES LORBER.
